UNITED STATES PATENT OFFICE.

EMMA TROXEL HOUTZ, OF McLEAN, VIRGINIA.

GUARD FOR SEWING MACHINES.

Application filed January 21, 1924. Serial No. 687,626.

To all whom it may concern:

Be it known that I, EMMA T. HOUTZ, a citizen of the United States, residing at McLean, in the county of Fairfax and State of Virginia, have invented certain new and useful Improvements in Guards for Sewing Machines, of which the following is a specification.

This invention relates to a device for use in connection with a sewing machine to prevent the cloth being stitched from coming in contact with any portion of the machine. It not infrequently happens that in the use of a sewing machine, the cloth being stitched will, through accident or oversight, become draped in such a manner as to come in contact with some lubricated part of the machine, whereupon it will become soiled, or there is likelihood of the cloth being torn or otherwise damaged if it comes in contact with a moving part of the machine mechanism. Therefore, the present invention has as its general object to provide guard aprons adapted to be arranged one at the back and the other at the front of a sewing machine and so draped as to preclude any liability of the cloth which is being stitched, finding its way to a position beneath the top of the machine or beneath the treadle thereof.

Another object of the invention is to so arrange the apron which is to be disposed at the front of the machine, that an intermediate or lap portion thereof may be maintained in properly draped position over the lap of the operator of the machine so as to prevent the cloth, which is being stitched, dropping to a position beneath the top of the machine and, on the other hand, maintaining the cloth in a neatly folded condition in the lap of the said operator.

Another object of the invention is to so construct the device that it may be readily applied to any sewing machine and adjusted for use.

In the accompanying drawings:

Figure 1 is a side elevation illustrating the manner of employing the guard embodying the invention;

Figure 2 is a vertical front to rear sec-

tional view through the front apron of the guard;

Figure 3 is a plan view of the front apron and the attaching means therefor;

Figure 4 is a view in front elevation of the front apron of the guard removed from the machine;

Figure 5 is a similar view of the rear apron of the guard removed;

Figure 6 is a view illustrating the compact manner in which the device may be arranged when not in use.

The front apron of the guard, which is best illustrated in Figures 1 to 4, inclusive, is indicated in general by the reference numeral 1 and the apron may be made up from any required number of cloth blanks and comprises a body portion 2 which is preferably of substantially rectangular marginal outline and is provided along its upper edge with a hem having a series of openings 3 therein through which screws or other securing elements 4 may be passed, this margin of the apron being laid over a wood strip 5 which is disposed against the under side of the top of the machine at the front and secured in place by the said securing elements 4. In this manner, the apron, which is of substantially the same width as the sewing machine top, is draped in front of the machine and its lower edge will nearly reach the floor.

The front apron 1 has its body portion or sheet cut away at its mid-portion, as at 6, to provide a limb receiving opening in the apron to permit of the apron being properly arranged with relation to the lap of the one operating the sewing machine. In thus providing the opening 6, which extends from a point near the upper margin of the sheet 2, downwardly and through the lower margin thereof, the lower portion of the sheet is divided into two side sections indicated by the numeral 7 which sections depend at the opposite sides of the front of the sewing machine substantially in a vertical plane and are provided at or near their lower outer corners with tie strings 8 or other means adapting the said lower outer cor-

ners to be attached to the front corners of the frame of the sewing machine as best shown in Figure 1. In order that the side sections 7 may be held substantially flat, it is preferable that transverse pockets 9 be formed in each of the said side sections parallel to their lower margins, and that stay 10 of metal, bone, or other material, be arranged within the pockets, as best shown in Figure 4.

The limb receiving opening 6 in the sheet 2 is preferably increased in width in the direction of its upper portion, and the said upper portion is defined by an approximately semi-circular hem which is indicated by the numeral 11. The numeral 12 indicates a lap apron which is stitched at its upper margin to the hem 11 and which is preferably provided with a fullness as illustrated in the drawings. This apron is of such depth that it may be draped over the lap of the operator of the machine as shown in Figure 1, being arranged likewise substantially as shown in Figures 2 and 3, and strings 13 are connected to the said apron near its free margin and adapted to be tied about the waist of the operator of the machine. By reference to Figure 1 it will be observed that due to the fullness provided in the lap apron 12, the said apron may be more or less closely draped over the lap of the wearer and yet without in any way interfering with the necessary limb movements in operating the machine.

The back apron is indicated in general by the numeral 14 and comprises a body sheet 15 of any suitable material, preferably the same as that from which the body sheet 2 of the front apron is formed. The back apron, like the front apron, is of substantially rectangular marginal outline and is provided with a marginal hem 16. Openings 17 are formed in the upper margin of the body sheet 15 and are designed for the passage of securing elements 18 corresponding to the elements 4 previously described, these securing elements being passed through a strip 19 of wood or other material over which the said margin of the sheet 15 is laid, and the said elements being driven into the under side of the top of the machine at the rear thereof. Tying strings 20 are connected to the lateral margins of the body sheet 15 near the lower corners thereof and may be suitably tied about the rear lower corners of the frame of the machine, and in this manner the rear apron 14 is maintained in a suitably draped position extending over the complete rear of the machine beneath the plane of the top and thereby preventing any of the cloth, being sewed, entering the space beneath the said top of the machine. If desired, a pocket 21 may be formed transversely in the lower portion 65 of the sheet 15 parallel to the lower edge and

extending between the opposite lateral edges of the said sheet, and a stiffening bar or the like indicated by the numeral 22 may be arranged within the said pocket.

From the foregoing description of the invention, it will be evident that the device embodying the invention is readily applicable to any sewing machine and constitutes an efficient means for preventing the cloth which is being stitched entering the space below the top of the machine where it would be liable to come in contact with lubricated or moving parts and thereby become soiled or torn. The invention is, of course, adapted for use in the home and also in factories and should prove highly effective in the latter use in view of the expected carelessness of the operatives.

As illustrated in Figure 6 of the drawings, the aprons may be rolled to compact form when the device is not in use and in order that they may be retained in this form, a strap 23 is stitched or otherwise secured at one end at the marginal portion of either apron and a snap fastener 24 is provided for separately connecting the two ends of the strap after the strap has been engaged about the rolled aprons.

Having thus described the invention, what is claimed as new is:

1. A guard for sewing machines comprising main and secondary members, the main member being provided with means adapting it to be attached at its upper edge to the top of the machine and at its lower edge to the lower portion of the machine, the main member having substantially its entire middle portion from top to bottom cut away to provide a gate-like opening to allow freedom for the operator's limbs, the secondary member being marginally united to the main member along the edge of the gate-like opening in order to overlay the lap and extend down the sides of the limbs of the operator.

2. A guard for sewing machines comprising main and secondary members, the main member being provided with means adapting it to be attached at its upper edge to the top of the machine and at its lower edge to the lower portion of the machine, and the main member having substantially its entire middle portion from top to bottom cut away to provide a gate-like opening to allow freedom for the operator's limbs, pockets being formed on each side of said gate-like opening in the main member, stiffening means inserted in the pockets, the secondary member being marginally united to the main member along the edge of the gate-like opening, and securing elements on the secondary member adapted to attach the same to the body of the operator in such a manner as to cover the lap and limbs of the operator.

3. A guard for sewing machines comprising

ing a main member and a secondary member, said main member including substantially rectangular side sections and a relatively narrow top section, means adapting the main member to be attached along its top edge to the working table of the sewing machine, the auxiliary member being fastened to the main member along the straight inner edges of said side sections and to the top section, and securing elements on the secondary member adapted to attach the same to the body of the operator in such a manner that it covers the lap and limbs of the operator.

5 In testimony whereof I affix my signature.

EMMA TROXEL HOUTZ. [L.S.]
